UNITED STATES PATENT OFFICE.

CHARLES WALTER EVANS, OF FORT THOMAS, KENTUCKY.

DESIGN FOR A HOOP-NAIL.

SPECIFICATION forming part of Design No. 33,740, dated December 18, 1900.

Application filed November 16, 1900. Serial No. 36,783. Term of patent 7 years.

To all whom it may concern:

Be it known that I, CHARLES WALTER EVANS, a citizen of the United States of America, and a resident of Fort Thomas, in the county of Campbell and State of Kentucky, have invented and produced a certain new and original Design for Hoop-Nails, of which the following is a specification.

Figure 1 is a side elevation of a hoop-nail embodying my invention. Fig. 2 is a top view of the same. Fig. 3 is a rear elevation of the same.

The principal features of my design are the outer face α and the inner face α' of the shank.

The outer face is oval in cross-section and the inner face is flat and straight. Upon each of said faces are a series of barbs α^2 . The shank meets the head at an acute angle. The head is flat, of the same thickness throughout, and is broader than the shank. 20

What I claim is—

The design for a hoop-nail as herein shown and described.

CHARLES WALTER EVANS.
